UNITED STATES PATENT OFFICE.

WALTER THOMAS, OF VANCOUVER, BRITISH COLUMBIA, CANADA.

GAS-GENERATOR.

No. 895,910.

Specification of Letters Patent.

Patented Aug. 11, 1908.

Application filed March 30, 1908 Serial No. 424,033.

To all whom it may concern:

Be it known that I, WALTER THOMAS, a subject of the King of Great Britain, residing in Vancouver, Province of British Columbia, 5 Dominion of Canada, have invented an Improvement in Gas-Generators, of which the following is a specification.

The object of my invention is to provide an improved apparatus for generating producer gas, water-gas, or carbureted water-gas, as may be required.

The apparatus is adapted to work under suction or pressure, and for utilizing various forms of gas-producing fuel, such as low 15 grade coal, coke, oil, tar, peat, saw-dust or refuse-wood, garbage, and other organic substances.

The apparatus is comparatively simple, and supplemental parts such as a carbureter 20 and checker brickwork ordinarily used for super-heating effects, are dispensed with. The gases are generated in three adjoining connected chambers or compartments into which the fuel is admitted and these are provided 25 at the bottom with valved pipes for admitting air or steam, and at the top with gas-eduction pipes, one for conducting producer gas into a holder alongside the generator and the other for conveying water-gas 30 or carbureted water-gas into another and separate holder, while blowers are provided for forcing in air, and returning producer gas through the generator for enriching it.

The construction, arrangement, and operation of parts are as hereinafter described and illustrated in the accompanying drawings, in which:

Figure 1 is a plan view of the apparatus; Fig. 2 is mainly a side elevation, a portion 40 being shown in section for illustration of interior construction; Fig. 3 is an elevation of the side opposite that shown in Fig. 2; Fig. 4 is a vertical cross section on the line 4—4 of Fig. 1; Fig. 5 is a vertical cross section on the line 5—5 of Fig. 1.

Referring particularly to Figs. 1 and 2, A, B, B' indicate three chambers or compartments for receiving fuel from which gas is to be generated. These chambers or compartments are elongated vertically and arranged side by side, being separated by partitions 1, which are provided at the top with transverse passages 2, which permit the flow of gas from the side chambers B, B', into the 55 central chamber A. I propose to employ in this apparatus any gas producing fuel, but it

may be particularly adapted for refuse saw-dust or refuse wood by cutting away the partitions 1, as indicated by dotted lines 3, in Fig. 5. In other words, by cutting away the partitions down to the point indicated by dotted lines 3, in Figs. 2 and 5, large openings or spaces 2 are provided which render the upper portions of the chambers inter-communicating and better adapt the apparatus for burning fuel containing a large amount of moisture. Each of the chambers is provided at the bottom with a grate 4 and a side opening 5 having a door for closing it, as shown in Figs. 3, 4 and 5. The openings 5 serve for introduction of a bar for removing clinkers from the grates 4. At the top of each chamber there is provided an opening 7 having a cap or cover 8, for admission of fuel.

The ash-pits of the several chambers A, 75 B, B' are provided with openings 9, as shown in Figs. 4 and 5, for removal of ashes. At the top of the central chamber or compartment A, there is a passage 10—see Fig. 2—the same being surmounted by a stack or 80 head 11, from which pipes 12 and 13 lead in opposite directions. The pipe 12 is for conveying off producer-gas into a gas-holder C, which may be located at any required distance from the generator, and the pipe 13 85 is for conveying water-gas, or carbureted water-gas, into a similar gas holder C'.

The pipes 14—see Figs. 1, 2, 3—are provided for conveying oil into the top of the central chamber A. As shown in Figs. 2 90 and 3, the terminals of these pipes are in the form of nozzles 14^a directed downward and at a slight angle so as to discharge convergently into the chamber A and in proximity to the passages 2 that communicate with the 95 side chambers B, B'.

Air is forced into each of the chambers by means of a pipe 15 having right angular branches 15^a arranged as shown in Figs. 4 and 5, the same having nozzles that terminate just below the grates 4. The pipe 15 is located on the back or rear side and below the base of the generators and extends along the same, being provided at its outer end with a fan or blower 16—see Figs. 1, 2, 3. 100

In Figs. 4 and 5 I show a steam pipe 17 having three branches 17^a, 17^b and 17^c, which lead to the ash pits of the several chambers A, B, B'. By this means steam may be discharged beneath the grates, either 110 alone or simultaneously with the discharge of air from the pipes 15, 15^a. Producer-gas

may be generated by the discharge of air alone up through incandescent fuel into the several chambers, but it is the more common practice to also discharge steam beneath the grates at the same time.

It is sometimes desired or required to enrich the producer-gas. For this purpose I employ a blower 18—see Figs. 1 and 2—which is located at one end of the generator 10 and connected with the producer-gas pipe 12 and a pipe 19 that extends along side of the several generating chambers and is provided with a series of horizontal branch pipes or nozzles 19^a—see Figs. 4 and 5—the 15 same discharging into the ash pits of the several chambers, so that the producer-gas may be carried up through incandescent fuel, as will be presently described.

In connection with the several pipes or 20 conductors for air, steam, and air, heretofore described, I employ a series of valves which are connected by rods with levers 20, all of which, for convenience of access and operation, may be arranged together, or side by 25 side, as shown in Figs. 2 and 4. Thus, the valve-cover 21 of the gas-head 11, of central chamber A—see Figs. 4 and 5—is pivoted at one side and connected by a link 22, with a rod 23—see Fig. 1—in turn connected with 30 and adapted to be rotated by one of said levers 20; similarly, the valves 24 and 24^a of gas-eduction pipes 12 and 13 are connected with, and operated by, rods 25 leading to and connected with others of the levers 20. 35 As shown in Figs. 2 and 3, a rotary valve 26 is applied to the air-pipe 15 contiguous to the fan or blower 16, and this is operated by a rod 27 also connected with one of the levers 20. Each of the branch pipes 15^a connected with the air-pipe 15, is similarly provided with valves 28 that are operated by rods 29 connected with certain levers 20. The pipe 19 through which the producer gas 40 is forced by the fan 18 when required to be enriched, is provided with a valve 30 operated by rods 31, and a lever suitably connected therewith. Each of the branch pipes 19^a connected with the pipe 19 is provided with a valve 32 and these several valves are 45 operated by rods 33 connected with certain levers 20.

It should be understood that this apparatus will ordinarily be operated as a suction apparatus; in other words, a suction fan 50 (not shown) will be connected with a top portion of the gas-holders or gasometers C and C'. On the other hand, the suction fan may be dispensed with and the apparatus may be used on the pressure system.

60 I will now briefly describe the general operation of the apparatus.

The gas-producing fuel is placed in all three generating chambers A, B, B', and ignited at the grate, and the stack valve 21 65 of the central chamber is opened and fan 16

is started so that air is blown through the pipe 15 and its branches 15^a into the several chambers beneath the grates thereof. When the fuel in the several chambers has become incandescent the stack valve 21 is closed, and 70 it need not be opened again, since all the producer gas may be, by subsequent blowing or blasting, conveyed by the pipe 12 into the holder C. Thus, as soon as the stack valve is closed, the producer-gas is rapidly generated and carried off through the pipe 12, as 75 will be readily understood. In such case, it is obvious that the valve of pipe 13, located adjacent to the head or stack 11, must be closed. To produce water-gas, the fuel 80 being incandescent in the several chambers, A, B, D', steam is admitted by pipes 17^a, 17^b, 17^c, beneath the grates, and the valve of producer pipe 12 being closed and the valve of the eduction pipe 13 being open, the water-gas 85 produced in the chambers will be conveyed into the holder C'. It will be observed that in all these operations the gas from the side chambers B, B' enters the central chamber through the partition openings 2. 90

In order to make carbureted water-gas, the fuel, being incandescent as before; steam is admitted under the grate of the center generator A, and oil is sprayed in at the same time through the nozzles 14^a, and mingles with 95 the water-gas proper, and the mixed gases pass laterally through the passages 2 into the two side chambers B, B' and then down through the incandescent fuel therein, thus becoming a fixed or permanent gas which is 100 taken off by the pipe 19, through the branches 19^a of said pipe and thus conveyed into the holder C'. Thus it will be seen that if water-gas only is required, steam is turned on in all the chambers, and the water-gas 105 passes out at the top through the pipe 13 into holder C; but if the gas is to be carbureted, then steam is admitted to the center chamber A only, and the mixed gases pass into the side chambers, and then down 110 through the grates thereof and through the pipes 19, 19^a, to the holder C'. 115

If it is required to enrich the producer-gas that has been received into the holder or gasometer C, it is brought back by the fan 18 and forced through the pipes 19, 19^a, into the gas-generating chambers, where it meets oil vapors introduced by the nozzles 14^a and thus passes enriched or carbureted over into the gas-holder C'. 120

Near the junction of the producer-gas eduction pipe 12 with pipe 19, I provide the former with a valve 34 for closing it when required, and in such case the fan 18 draws the producer-gas back through branch pipe 12^a. 125

What I claim is:

1. A gas-generating apparatus comprising a series of fuel-receiving and gas-generating chambers, the said chambers communicating by transverse passages and the central one 130

having a discharge head or stack, pipes for producer and water-gas connected with said head and each provided with a valve for controlling the flow of gas therein, holders for producer and water-gas, respectively, with which the said pipes communicate, oil pipes arranged in the upper portion of the central chamber for discharge of oil thereinto, and air and steam pipes connected with the bases 10 of the chambers for discharging air and steam beneath the fuel therein, substantially as described.

2. The improved gas-generating apparatus comprising two or more communicating gas-generating chambers, a hollow head or stack applied to the top of one thereof, producer- and water-gas eduction pipes connected with said head and provided with valves for controlling the flow of gas therein, holders for 15 producer- and water-gas respectively, with which such pipes communicate, and means for returning producer gas for enriching the same, such means consisting of a pipe communicating with the producer-gas eduction 20 pipe and extending into the chambers beneath the fuel grate thereof and provided with valves for controlling discharge of gas, and a blower connected with such pipe, and a valve for opening and closing said pipe which 25 latter connects with the water-gas eduction 30 pipe, as shown and described.

3. A gas-generating apparatus comprising two or more communicating fuel-receiving and gas-generating chambers, eduction pipes 35 connected with one of said chambers for conducting producer and water-gas, and holders for receiving the gases, means for returning the producer-gas for enriching the same, such

means consisting of a pipe having branches extending beneath the fuel grates and provided with valves for controlling discharge of producer-gas into the chambers, and a blower connected with such pipe and the latter connected with the aforesaid eduction 40 pipe, as shown and described. 45

4. The improved gas-generating apparatus comprising a series of gas-generating chambers having communicating lateral openings, the central chamber provided with a hollow head, producer- and water-gas 50 eduction pipes connected with such head and provided with valves for controlling flow of gas therethrough, holders for producer and water-gas with which said pipes respectively communicate, air and steam pipes arranged 55 to discharge beneath the grates of the several chambers, said pipes being provided with valves for controlling the flow of air and steam, a blower connected with the main air pipe, and means for returning and enriching 60 producer-gas, the same consisting of a main pipe connected with the usual producer-gas eduction pipe and having branches extending into the bases of the several chambers and provided with valves for controlling the 65 flow of producer-gas into the chambers, and a blower applied to the producer-gas return pipe, the latter being connected with the water-gas eduction pipe and having a valve for opening and closing it, substantially as 70 described.

WALTER THOMAS.
